UNITED STATES PATENT OFFICE.

NEWTON RICHEY, OF ASHLAND, OHIO.

THILL-COUPING.

SPECIFICATION forming part of Letters Patent No. 320,817, dated June 23, 1885.

Application filed October 25, 1884. (No model.)

To all whom it may concern:

Be it known that I, NEWTON RICHEY, of Ashland, in the county of Ashland and State of Ohio, have invented a new and useful Improvement in Thill-Couplings; and I do hereby declare that the following is a full, clear, and exact description of the same.

My invention is an improvement in thill-couplings of that class in which the bolt holding the shaft-iron to the socket is held in place by a movable stop, whereby the shaft-iron is held securely against accidental displacement, but is easily removed whenever it is desired to remove the shafts.

15 The invention consists in details of construction hereinafter described and claimed, the purpose of which is to provide a simple construction of easy manufacture, which construction will also furnish a secure hold of the shaft-iron and a constant spring-pressure against said iron to prevent rattling.

20 In the accompanying drawings, Figure 1 is a perspective view of the entire coupling. Fig. 2 is a section through the clip-socket and shaft-iron and also through the spring-bolt and pressure-plate. Fig. 3 is a section taken longitudinally through the coupling on the line with the bolt and the pressure-bar.

25 A clip, A, of ordinary construction, surrounds the axle. Integral with or connected to this is a socket-piece, B, the sides *a a* of which extend downwardly forming downwardly-projecting ear or ears *b b*. Upon these sides the eye *c* of the shaft-iron fits snugly. Holes 30 in the sides, adapted to register with holes in the eye *c*, admit the bolt *d*, the head of which is countersunk into the side. In the lower ends of the ears *b b* are holes made directly opposite each other to receive the pressure-bolt *e*. One end of this bolt is provided with 35 a head or nut, and upon the other end is a stop-arm, *g*, the arm being fixed to the bolt. The upper end of this arm is adapted to swing over and close to the outer face of the side *b*, which 40 is countersunk for the head of the bolt *d*.

45 The upper end of the arm *g* is provided with offsets *h*, which, when the arm is swung up to cover the head of the bolt *d*, fits snugly over the upper edge of the side *b*. This offset is provided with a locking-pin, 1, on a reduced shank, and within a hole in the offset is a spring, 2.

The upper end of the shank is provided with

a head, 3, and the spring tends to force out the pin 1 into a hole, 4, in the upper edge of the side. This pin holds the plate *g* over the end 55 of the bolt *d* and prevents it from coming out. In order to remove the bolt, the head 3 is lifted and the spring thus withdrawn, when the plate may be sprung before uncovering the countersunk head of the bolt *d*.

60 The pressure-bolt *e* is cut away, as shown at 5, on the side opposite that in which the arm extends—that is to say, when the arm covers the bolt and is locked in place the rounded side is uppermost and the flat or cut side is underneath.

Between the ears *b b* or lower part of the sides *b b* is a pressure-plate, H. This plate has front and rear flanges, 6 and 7, which extend up the edges of the ears, so that the plate 70 rests upon the pressure-bolt and is held against displacement to front or rear by these flange-extensions, (marked 6.)

A spring, *l*, of rubber or equivalent material, is held in the pressure-plate between the 75 flanges and the sides *b b*, and a piece against the lower surface of the eye shaft-iron.

When it is desired to connect the shaft to the clip, the arm *g* is thrown down to a vertical dependent position, and the vertical plate 80 rests upon the cut-away portion of the pressure-bolt, being thereby lowered, and with it the spring is also lowered. The eye of the shaft-iron is then introduced and the bolt *d* inserted. The arm *g* is then brought up to its 85 place to cover the end of the bolt until the pin is forced into the hole. This turns the pressure-bolt with its rounded side up, raising the plate, and puts the spring under compression.

The bolt is easily made by cutting away an 90 ordinary iron bolt.

The construction of the pressure-plate is such that the spring is held securely, but may be easily removed.

The parts may be all formed cheaply and 95 work securely when in place.

I claim as my invention—

1. In a thill-coupling, in combination with a socket, the eye of the shaft-iron, the bolt connecting the eye to the socket and the stop-arm which holds the bolt, the pressure-bolt fixed to the arm, and cut away on one side, and the pressure-plate and spring, substantially as described.

2. In a thill-coupling, the combination, with
a socket, of the pressure-bolt and stop-arm
provided with a locking-spring, the pressure-
plate H, resting upon the pressure-bolt, the
5 said plate having flanges 66, extending across
at the front and rear between the sides of the
socket, and the spring 7, interposed between
the pressure-plate and the eye of the shaft,
all substantially as described.

In testimony whereof I have signed my name to
this specification in the presence of two sub-
scribing witnesses.

N. RICHEY.
